UNITED STATES PATENT OFFICE.

THOMAS E. MURRAY, OF BROOKLYN, NEW YORK.

FORMING OF HOLLOW ARTICLES.

Application filed June 20, 1924. Serial No. 721,181.

In my application No. 679,521 and certain other pending applications, I have described the use, for forming ducts of concrete or the like, of a core of rubber or similar resilient, flexible material, such that when pulled lengthwise it will contract transversely sufficiently to detach it from the surrounding concrete and to permit its withdrawal, and when released it will resume its original shape; the core being preferably used without mandrel or other reinforcing means, and being of such dimensions that it will support the pressure of the surrounding concrete. My present invention aims to utilize similar resilient, flexible cores in the moulding or shaping of hollow articles of metal, or composed at least in part of metal. The accompanying drawings illustrate embodiments of the invention.

Fig. 1 illustrates a T or branch in a concrete body lined with metal and formed by my present invention.

Fig. 2 illustrates in perspective the core and the metal lining for the structure of Fig. 1.

Fig. 3 illustrates in perspective the core alone.

Fig. 4 illustrates in perspective a core for a straight tube.

Figs. 5 to 9 illustrate in perspective successive stages in the forming of an elbow of insulated metallic tubing.

Fig. 10 is an enlarged end view of Fig. 8.

In Fig. 1 a body of concrete 1 has a longitudinal duct connected with a lateral branch, the longitudinal and lateral portions being continuously lined with a thin coating or plate 2 of copper. In the making of such an article we start with a core shown in Fig. 3 and composed of two parts 3 and 4, held together by any suitable means along the line 5. These parts are made of rubber tubing of a highly resilient composition and with walls thick enough to stand all the strain to which they may be subjected, and thus to prevent deformation of the thin coating of copper referred to below. Such a core is coated with a layer or plate 6 (Fig. 2) of copper, which ultimately forms the lining 2 of the finished article. The metal may be deposited electrolytically on the core. For this purpose the core 3 and 4 should first be protected by an insulating coating 7. Outside of this should be applied a layer of graphite 8 to take the deposit of metal 6. The metal-coated rubber core thus formed

will then be surrounded by concrete. The pieces 3 and 4 of the rubber core will then be pulled out endwise. When the end of the core is pulled, the rubber is extended lengthwise and contracted in cross-section, so that it separates from the surrounding metal sufficiently to permit it to yield to the pull and thus be withdrawn, leaving a very thin lining 2 of copper adhering to the inside of the tubular concrete structure. The body of the article may be made of other material than concrete. The same is true of the metallic lining, which may be made of various metals capable of electric deposition.

The invention may be applied also to the product of a simple metal article. For example, in Fig. 4 there is shown a rubber core 5 with a protective coating 7, graphite 8, and a deposited coating 9, consisting of a straight metal tube. The ends of the core are plugged with corks 10 during the deposition of the metal. The rubber core may be withdrawn, leaving merely a tube of metal of a thickness controllable in the electrolytic operation.

The metal or other materials may be applied to the core in various ways. In Fig. 9 I have illustrated a bent metal tube with a lining 11 of plastic or compound insulating material adapted to carry electric cables or wires. This may be made by the succession of steps illustrated in Figs. 5 to 8. A tubular core 12 is wound with a strip of woven fabric 13 in conjunction with a plastic material to hold it in place, such as is used in making similar insulation on electric cables. Or the woven fabric may be used in conjunction with strips of rubber.

Outside of the coating of fabric or fabric and plastic there are wound (Fig. 6) strips of very thin copper 14 overlapping one another. The tubular structure thus built up can be bent to any desired shape. Fig. 7 shows it bent to a simple elbow. The character of the materials is such that it will bend easily and will maintain its bent shape. The form thus produced, in effect a compound flexible mandrel, is then fixed in shape, as for example, by immersing in zinc 15 (Fig. 8) or in other metal or concrete, porcelain or the like.

The core 12 is then pulled, contracting it in cross section and separating it from the surrounding material and finally withdrawing it, leaving the tube (Fig. 9) with the

outer shell of cast zinc 15 and the compound inner coating of textile, plastic and copper indicated as a whole at 11.

For some uses the outer heavy coating of zinc or other metal may be omitted. Also the wound copper may be omitted; the tubular structure of fabric and plastic being of such composition that it will stiffen sufficiently for use, or being immersed in or treated with material which will stiffen it, so as to permit the withdrawal of the resilient core.

Though I have described with great particularity of detail certain embodiments of my invention, yet it is not to be understood therefrom that the invention is restricted to the particular embodiments disclosed. Various modifications thereof in detail and in the arrangement of the parts may be made by those skilled in the art, without departure from the invention as defined in the following claims.

What I claim is:

1. The method of moulding hollow articles composed at least in part of metal, which includes shaping the metal part to tubular form on a core of resilient flexible material adapted when pulled lengthwise to contract in cross-section and thus separate from the surrounding material and pulling said core out of the article thus formed.
2. The method of moulding hollow articles composed of metal and plastic material which consists in shaping the metal to tubular form and also shaping the plastic material to tubular form on a resilient core and withdrawing the core.
3. The method of moulding hollow articles composed at least in part of metal, which consists in shaping metal on a resilient core, forming a body of plastic material around said metal and withdrawing said

core, leaving the metal as a lining in the body of plastic material.

4. The method of moulding hollow articles composed at least in part of metal, which consists in depositing metal on a resilient core, forming a body of plastic material around said metal and withdrawing said core, leaving the metal as a thin lining in the body of plastic material.

5. The method of moulding hollow articles which consists in laying the material of such articles about a core of resilient flexible material, bending the whole to the desired shape, fixing the material in the desired shape and withdrawing said core.

6. The method of moulding hollow articles which consists in laying the material of such articles about a core of resilient flexible material, bending the whole to the desired shape, applying metal to the material to fix the shape and withdrawing the core.

7. The method of moulding hollow articles which consists in laying insulating material about a core of resilient flexible material, bending to the desired shape, applying metal to the insulating material and withdrawing the core, leaving a tube of metal with insulating lining.

8. The method of moulding hollow articles which consists of shaping flexible material to tubular form on a resilient flexible core adapted when pulled lengthwise to contract in cross-section and thus separate from the surrounding material, stiffening said flexible material in the said tubular shape and pulling said core out of the surrounding material.

In witness whereof, I have hereunto signed my name.

THOMAS E. MURRAY.
